UNITED STATES PATENT OFFICE.

PERLE T. HAMBRIC, OF SUTTER CREEK, CALIFORNIA, ASSIGNOR OF ONE-HALF TO WILTON E. DARROW, OF SUTTER CREEK, CALIFORNIA.

CONCENTRATING APPARATUS.

No. 878,879.

Specification of Letters Patent.

Patented Feb. 11, 1908.

Application filed September 30, 1907. Serial No. 395,236.

To all whom it may concern:

Be it known that I, PERLE T. HAMBRIC, citizen of United States, residing at Sutter Creek, in the county of Amador and State of California, have invented new and useful Improvements in Concentrating Apparatus, of which the following is a specification.

My invention relates to apparatus for concentrating the metalliferous particles of value-bearing ores, and pertains especially to a type of apparatus known as canvas-plants.

The main purpose of an apparatus of this character is to effect an efficient primary concentration to bring up the percentage of values from say fifty cents or a dollar a ton to four or five dollars a ton, so as to render profitable the future handling of naturally low grade ore.

The object of this invention is to provide a continuous, automatic, self-washing canvas-plant of large capacity, which shall take up little room, and which shall be cheap to manufacture and install, and economical of maintenance.

The invention consists of the parts and the construction and combination of parts as hereinafter more fully described and claimed, having reference to the accompanying drawings, in which—

Figure 1 is a vertical section of my apparatus taken on line X—X of Fig. 2. Fig. 2 is a plan view of same.

A represents a suitable central supporting shaft or column carrying the frame 2, which is of any appropriate description, and on which is mounted one or more series of annular tables or concentrating surfaces 3—3'—3^a, etc. The frame is suitably braced, as by the stay-rods 2', which are adjustable by the turnbuckles 2^a.

The tables or concentrating surfaces 3—3', etc., are arranged circumferentially of the frame 2, and each table is covered with canvas or other suitable material to which the heavier particles of ore and metal will cling. The tables of each series comprise successive segments with a discharge over their outer edge, which discharge is accomplished by gravity and centrifugal force, or by centrifugal force alone. However, it is to be said that the rate of rotation of the frame 2 is not such as to operate against a proper degree of concentration. Any appropriate means may be employed to rotate the tables, as, for example, the worm gearing a.

Each series of tables may be made adjustable to vary the inclination of the tables; the tables being pivoted to frame 2 at 4 and being adjustable by the screws 5, which fit slots 6 in fixed parts of the frame 2.

There are as many series or decks of these tables mounted on the one frame and all revolving in unison, as may be desired, or as the requirements of the mill may demand.

I have here shown a plural series of tables, 3—3'—3^a, arranged one above the other, for the purpose of handling a large output in a minimum amount of space. Manifestly this number may be increased or diminished as circumstances require. The invention comprehends, also, the use of one series alone.

Arranged above the inside edge of the series of tables is a series of continuous launders 7—7'—7^a, corresponding to the several table series, and which launders are supported by, and rotate with, the frame 2. The bottom of each launder 7 is made with a series of alternately upward and downward inclinations or undulations, with a high part of the bottom of a launder adjacent the meeting edges of two tables, and the bottom sloping off each side to the opposite edges of this same pair of tables. From each depression in each launder leads a delivery pipe 8 which discharges into a respective distributing box 8'. Each table of each series has a like distributing box 8'.

From a box 8' the water and material is distributed to two subjacent tables by a corresponding distributing plate 9. The plates 9 are preferably provided each with a series of radiating ribs or ripples 10, by which the material is equitably distributed to all parts of these particular tables. The distributing plates 9 and the boxes 8', like the launders 7, etc., are fixed to, and rotate with, the frame 2.

The launders are preferably all arranged in the same plane, as shown, for compactness, and for other practical reasons.

Each series of tables has its own launder, and each depression of each launder has its corresponding box 8' and distributing plate 9 feeding to a corresponding pair of tables. By this arrangement there are half as many distributing boxes and distributing plates for each series of tables as there are tables in the series.

The delivery into a box 8' takes place at the top, and the discharge therefrom prefer-

ably takes place from the sides; and the size of the box is such that the material and water delivered thereinto will be momentarily in such a confined space, that as it 5 flows out at the side on to the distributing plate, the riffles 10 will split the material and water up into a number of equal streams, so that each part of each table will get an equal share of material and water, irrespective of 10 the rotative action of the frame. Without the use of the riffles 10 there would be a tendency for all the material to bank up against one side of one of the tables.

Any suitable means may be employed to 15 deliver the material in suitable quantities into each launder. As here shown, I have arranged a series of stationary segmental troughs 11—11^a—11^b above and relative to the launders, and have connected each one 20 of these troughs at suitable intervals with a corresponding launder 7—7', etc., through suitable conduits 12—12'—12^a. These feed troughs receive the material to be acted upon by the apparatus from any source of supply, 25 as at b. The troughs are supported independent of the rotating frame, and the connections 12, etc., are such that delivery from the troughs will take place continuously into the respective launders. These feed troughs, 30 however, do not extend entirely around the apparatus, but a suitable space indicated between the ends 13—14 of the troughs is left, in which space the collection of the values on the tables may take place, as will be 35 explained shortly.

15 is a water-pipe arranged over each series of tables between the ends 13—14 of the feed troughs. This pipe is perforated and adapted to discharge a spray of water 40 on to the tables to wash off the concentrated values thereon, as each table comes beneath the spray of that series. Usually the space between the ends of the feed troughs will correspond to two or three table sections, 45 and it is during the traverse of the tables through this space that the sprays act on the tables and wash off their collected values. Of course, during the time that the tables are passing through this space between the 50 ends of the troughs, no new material is being delivered on to these particular tables.

When the tables to be sprayed off have passed beyond the end 13 of the feed troughs they cease to receive any more pulp, but 55 they begin to receive an equal volume of clear water from a stationary pipe 19, which discharges into the several launders 7—7', etc. This clear water passes directly down on to the respective tables of the several 60 series and serves to remove the remaining waste and gangue on the tables, before spraying off the minerals and other values.

Under some circumstances it may be arranged that the different launders may deliver different grades of material to the sev-

eral tables; or one launder may deliver the same grade to a plurality of tables. In the latter case, of course it might be desirable or necessary to correspondingly increase the size and carrying capacity of that particular 70 launder, and it would receive a correspondingly increased supply of clear water at the right time from the clear water pipe 19. The several wash water pipes 15 and 19 may connect with the supply pipe 20, and each pipe 75 may have its regulating cock 21.

The tables may be covered with any suitable value-saving and collecting material, such as canvas, and any appropriate means may be employed to detachably secure the 80 canvas to the table.

Where the tables are made individually adjustable, so as to permit the variation of the incline of the tables, suitable end guide strips 16 are employed to prevent the material 85 over-flowing the ends of the tables.

In operation, the frame 2 is set in motion and revolved at substantially uniform speed; the speed to be determined by the size of the machine, and the characteristics of the ore 90 handled. The pulp is delivered at b into the troughs 11—11^a—11^b, and thence fed through the flexible connections 12—12'—12^a, into the respective launders 7 of the several series of tables. Each launder 95 delivers into its boxes 8', and these boxes discharge on to their respective distributing plates 9, which in turn spread the material to corresponding pairs of tables. By the feed of water, and the centrifugal action, the 100 worthless material is discharged over the rim of the tables, the values and heavier particles of ore collected in the canvas fabric. This separation of the worthless material from the more valuable material takes place 105 during the passage of the tables around the length of the feed troughs. During that period that no fresh material is delivered on to the tables, the clear water from pipe 19 removes the residue of gangue, and then the 110 sprays from the pipes 15 act to wash off the valuable collections on the tables into suitable stationary collecting troughs 18.

It is understood that the purpose of this apparatus is to make a rough or primary 115 concentration, and it is for use especially with low grade ores.

The stuff collected in the trough 18 has such a percentage of values that its future treatment by more complete concentrating 120 methods is rendered profitable.

This apparatus is practically continuous, and requires little or no attention, and needs but little power to run it.

By arranging the tables in deck formation, 125 one above the other, maximum capacity is had in a minimum amount of space.

Having thus described my invention, what I claim and desire to secure by Letters Patent is—

1. In an apparatus of the character described, the combination of a rotatable frame, a horizontal launder, revoluble with said frame, an annular series of tables arranged below the launder and revoluble therewith, said series of tables being disposed one above the other, and each of said tables having a distributing plate proximate to its inner edge, and adapted to distribute material for each pair of adjacent tables, and a feed box delivering on to said plates, said launder having divisions corresponding to the respective series of tables and said divisions having feed pipes leading to respective feed boxes. 5
2. In an apparatus of the character described, the combination of a rotatable frame, a horizontal launder revoluble with said frame, an annular series of tables arranged below the launder and revoluble therewith, said series of tables being disposed one above the other and each of said tables having a distributing plate proximate to its inner edge and adapted to distribute material for each pair of adjacent tables, a feed box delivering on to said plates, said launder having an undulating bottom and one of the feed boxes being disposed beneath each undulation of the launder, a stationary feed trough delivering into a portion of the length of the launder, and means for removing the concentrated values on the tables during the rotation of the frame. 10
3. In an apparatus of the character described, the combination of a rotatable frame, a horizontal launder revoluble with said frame, an annular series of tables arranged below the launder and revoluble therewith, said series of tables being disposed one above the other and each of said tables having a distributing plate proximate to its inner edge and adapted to distribute material for each pair of adjacent tables, a feed box delivering on to said plates, said launder having divisions corresponding to the respective series of tables and said divisions having feed pipes leading to respective feed boxes, 15 and means for varying the inclination of the several tables.
4. In an apparatus of the character described, the combination of a rotatable frame, a horizontal launder revoluble with said frame, an annular series of tables arranged below the launder and revoluble therewith, said series of tables being disposed one above the other and each of said tables having a distributing plate proximate to its inner edge and adapted to distribute material for each pair of adjacent tables, a feed box delivering on to said tables, said launder having an undulating bottom and one of the feed boxes being arranged beneath each of said undulations. 20
5. In an apparatus of the character described, the combination of a rotatable frame, a horizontal launder revoluble therewith, an annular series of tables below the launder and revoluble with the same, and each of said tables having a distributing plate proximate to its inner edge and adapted to distribute material for each pair of adjacent tables, a feed box delivering on to said plates, said launder having divisions corresponding to the respective series of tables and said divisions having feed pipes leading to respective feed boxes, 25 and means for removing the concentrated values on the tables during the rotation of the frame. 30
6. In an apparatus of the character described, the combination of a suitably supported, worm-gear-driven rotary frame, an annular launder carried by the frame and having an undulating bottom with discharge openings in the depressions of the launder, a series of tables arranged circumferentially of the support on to which said launders deliver, a fixed segmental feed trough extending part way around the launder and discharging thereinto at suitable intervals, a clear water pipe delivering into the launder between the ends of the feed trough, and a stationary spray pipe discharging on to the tables between the ends of the feed trough and acting on the tables subsequent to the clear water from said clear water pipe, for removing the values from the table. 35

In testimony whereof I have hereunto set my hand in presence of the subscribing witnesses.
